UNITED STATES PATENT OFFICE

LOUIS FRANCIS, OF ASHEVILLE, NORTH CAROLINA, ASSIGNOR TO WESTINGHOUSE ELECTRIC AND MANUFACTURING COMPANY, A CORPORATION OF PENNSYLVANIA

DESIGN FOR A RADIOCABINET

Application filed May 27, 1929. Serial No. 31,420. Term of patent 3½ years.

To all whom it may concern:

Be it known that I, LOUIS FRANCIS, a citizen of the United States, residing at Asheville, in the county of Buncombe and State of North Carolina, have invented a new, original, and ornamental Design for Radiocabinets, of which the following is a specification, reference being had to the accompanying drawings, constituting a part hereof.

Figure 1 of the drawing is a perspective

view of a radiocabinet illustrating my new design, the doors thereof being shown in the closed position.

Fig. 2 of the drawing is a similar view of the radiocabinet shown in Fig. 1, the doors thereof being shown in the open position.

I claim:—

The ornamental design for a radiocabinet substantially as shown and described.

LOUIS FRANCIS.
